UNITED STATES PATENT OFFICE.

ALLAN J. GROSS, OF CHICAGO, ILLINOIS, ASSIGNOR TO JOHN L. KENNEDY, OF CHICAGO,
ILLINOIS.

DRY-PIPE VALVE.

1,311,388.

Specification of Letters Patent. Patented July 29, 1919.

Application filed November 2, 1914. Serial No. 869,948.

To all whom it may concern:

Be it known that I, ALLAN J. GROSS, a citizen of the United States, residing at Chicago, in the county of Cook and State of Illinois, have invented certain new and useful Improvements in Dry-Pipe Valves, of which the following is a description.

My invention belongs to that general class of devices known as dry pipe valves, adapted to be used in automatic sprinkling systems, and particularly in the systems known as dry pipe systems, to be placed in the water supply pipe, the pressure of the water against the valve being opposed by an air pressure within the system. The invention has among its objects the production of a device of the kind described that is simple, compact, durable, efficient and satisfactory, which is positive in action, and which will be operative at all times and will not get out of order. It particularly has among its objects the production of a new and novel mechanism for locking the valve open, and preventing its closing at any point between the closed position and wide open position. It has also among its objects the production of a device in which there may be an unobstructed flow of water through the system, and one in which stones or other foreign materials cannot lock the valve against opening. Among other objects is the production of a device of the kind described with a simple and reliable alarm controlling device for indicating an abnormal condition at the valve. Other objects and advantages of the construction will appear to those skilled in the art from the disclosure made herein.

To this end my invention consists in the novel construction, arrangement and combination of parts herein shown and described, and more particularly pointed out in the claims.

In the drawings, wherein like reference characters indicate like or corresponding parts,

Figure 1 is a sectional view of my improved valve, taken substantially on line 1, 1 of Fig. 3;

Fig. 2 is an enlarged view of the alarm controlling device shown in Fig. 1.

Fig. 3 is a sectional view taken substantially on line 3, 3 of Fig. 1, and

Fig. 4 is a sectional view taken substantially on line 4, 4 of Figs. 1 and 3.

55 Referring to the drawings, in which the

preferred form of my device is shown, 1 represents a suitable casing provided with an inlet 2 and outlet 3. As shown, inlet 2 is formed in a separable casing end 4, suitably secured to the casing in any desired manner. 60 The casing is preferably provided with a hand hole 5, as shown. Arranged at the inlet on the inner side of the part 4 is a valve seat 6, preferably of bronze or other material that will not corrode. Arranged to co- 65 operate with the valve seat 6 is a valve 7, which is also preferably constructed of non-corrodible material, such as bronze or the like. The valve 7 is formed with a flange 8 thereabout, which carries a ring 9, forming a valve part. The ring 9 is preferably of flexible material, rubber being found very satisfactory for the purpose. The same is in the form of a ring and maintained in position on the flange 8 by a ring 12, suitably 70 secured in place. The flexible valve member 9 is arranged to seat on a valve seat 10 arranged at the end of the extension 11 on the part 4. As shown, the valve seats 6 and 10 are formed separable from the parts 4 75 and 11, so that they may be renewed from time to time should occasion require. In addition this construction permits the seats to be made of non-corrodible material, while the casing parts may be made of cheaper 80 material. While the ring 10 may be made of any suitable material, I prefer to use tin for that purpose. The valve member 7 is carried by an arm or lever 15, which is suitably pivotally secured to the casing. In 85 the preferred construction I adjustably secure the valve 7 to the lever 15 by a bolt 17 and spring 18, or equivalent means.

In practice the upper face of valve seat 6 is called the lower water seat, and the co-operating face of the valve 7 the upper water seat. The seat 10 is termed the air seat and the chamber 13 between the two seats being known as the neutral chamber. As most clearly shown in Fig. 1, a main drain 100 outlet may be provided as at 14, or at some other suitable point. The purpose of the main drain outlet is to permit the draining of the system, the water being piped away in any suitable manner.

The casing 1 is extended at one side as at 20, one side 21 of the extension being preferably detachable and secured in place in any desired manner. It will be noted by referring to Figs. 3 and 4 that the part 20 110

forms or contains a chamber, the same being separated from the interior of the main casting by the partitions 22 and 23.

Arranged within the chamber formed by 5 the extending part is a shaft or support 16, which is supported at its ends by part 22' of the casing and the extending bracket 24, or the equivalent (see Fig. 4). It will be noted by referring to Figs. 3 and 4, that a 10 pair of bearing rings 16' are arranged at each end of the shaft 16. The wall 22' is also provided with an opening, through which the shaft 16 may be removed as desired. The opening is normally closed by 15 a plug 20'. Secured on shaft 16 is the end of the lever 15, which in the construction shown is provided with an extending part or sleeve 19, which projects through the opening or hole 25 in the wall 22. The 20 sleeve 19 at the end on the interior of the chamber formed by the part 20, side 21, and walls 22, 23, is formed with an extending part 26, having or terminating in a lip 27 (see Fig. 1). The part 26 may be of non- 25 corrodible material, as the lip 27 is preferably of non-corrodible material. Secured to part 19 is a counterbalance member 28, the same being formed of suitable material and provided with an arm 29, having its 30 lower end formed as at 30 for attachment to the part 19. In the preferred construction I form 28 substantially cup-shaped and fill the recess with lead 31, or the like. This affords considerable weight to the counterbalance, and yet its size is minimum. Carried by the lip 27, and arranged to coöperate therewith, is a locking member or strut 32, having its lower end 32' formed with a 35 groove or recess arranged to seat on the lip 27. Of course the groove and lip may be interchanged if desired. The parts 32 and 32' are shown connected by a web or arm 33, and may be provided with a chamber, to be filled with lead 34 to increase the weight 40 of the same. The member or strut 32 has its outer end or face 35 preferably formed to substantially conform with the inner face of the part 20, which is preferably provided with a lining or face 36 of non-corrodible 45 material. In constructing the device, it may be mentioned that the center of curvature of the cylindrical face 36 is preferably the center of the shaft 16. The locking member 32 being mounted or arranged off the center, or 50 eccentric, forms a brake, locking the valve against closing, as will be more fully described hereafter. The chamber in part 20 is provided with an outlet, normally closed 55 by a plug 38, the purpose of the same being 60 hereafter described.

I have shown part 4 provided with a drip outlet 39. The purpose of the drip outlet is so that any water that may seep through between the valve 7 and seat 6 may escape, thereby preventing the accumulation of wa-

ter in the chamber 13, and any pressure therefrom on the underside of the valve, and the same also serves as an alarm port. I have shown means for automatically controlling this outlet and controlling an alarm 70 when the same is operated under abnormal conditions. Referring particularly to Figs. 1 and 2, a casing 40 is secured to part 4 at the outlet drip 39, the same being formed with a valve seat 41. Positioned within the 75 casing and arranged to coöperate with the valve seat 41 is a valve 42 having a stem 45, the valve being provided with guiding legs or wings 43 and 46. The stop 44 may be arranged as shown to limit the upward movement of the valve, if so desired. The valve is normally maintained open by a counterbalance member or lever 48, supported on a part 47, carried by the casing 40, or the equivalent. The part 48 has an extension 49 80 arranged to coöperate with the bottom of the valve, and is formed with a shoulder 50, which coöperating with the casing 40, limits the movement of member 48 on its support and supports the valve 42 at the desired 85 position.

The part 48 is suitably chambered, and arranged therein is a part 51 of suitable material provided with a chamber 52, the part 51 being maintained in position by the 95 plug or closure 53, or equivalent means. Contacts 54 and 55 suitably connected with conductors 56 and 57, which connect with a suitable source of energy, and alarm devices arranged where desired, are extended within 100 the chamber 52. In order to bridge the contacts 54 and 55 upon movement of member 48 when the valve is closed, I place a suitable quantity of mercury 58, or its equivalent, within the chamber 52. As is obvious, 105 when the valve is depressed the mercury is projected to the opposite end of the chamber 52, bridging the two contact points and closing the circuit thereat.

The operation of the valve and allied 110 parts may be briefly described as follows: Assuming that the valve and parts are in the positions shown: If air is placed in the system end of the device, filling the chamber and the casing above the valve, the pressure 115 forces the valve 7 down upon its seat 6, as well as forcing the part 9 upon the seat 10. It may be mentioned that water may be, and is preferably placed in the casing above the valve, so as to form a water seal before air 120 pressure is applied in the system. The adjustable connection between the valve and lever 15 permits the valve 7 to make the final movement to seat upon 6 without moving the lever. Any water that seeps or 125 passes past the seat 6 is discharged through the outlet 39. Should there be a sudden rush of water for any reason whatever, either caused by the opening of the valve 7 or by excessive leakage, the same will close 130

the valve 42, at the same time closing the alarm circuit, signaling to wherever desired that the valve 42 has been closed and that the system is not in its normal condition.

5 Assuming that this has been caused by the valve opening, owing to the reduction in the air pressure in the system due to the opening of the sprinkler heads caused by a fire: The air pressure being reduced, valve 7 opens to 10 admit water to the system. If the valve 7 was not locked open or prevented from closing when the column of water above the valve was of sufficient weight to be greater than the water pressure at the inlet 2, the 15 column of water would securely maintain it closed if the valve closed. With my device, however, as the valve opens, the lip 27 through the lever 15 and sleeve 19 is dropped, at the same time permitting the 20 locking member or strut 32 to drop the entire strut, including the braking face 35, moving down the braking face 36 of the part 25 to 20. If there is a tendency of the valve to close, however, lip 27 immediately causes the locking member to engage with the face 36, locking the valve against a closing movement. It will be noted that the more pressure on the valve the greater the thrust of the locking member against the face 36; in 30 other words, the greater the pressure the more positive the lock. The locking member is operative at any point during the movement of the valve from its closed position until it is wide open. This is important, as with this improved locking mechanism there can be no chattering of the valve, as it is free to move only in the opening direction. It will be noted by referring to Fig. 1 that when the valve is in its open position there is an unobstructed flow of water 40 from the inlet through the casing and out through the outlet.

The locking mechanism being substantially in a separate chamber, and inclosed, 45 cannot be rendered inoperative by stones or foreign material getting in between the parts and locking them against operation. In this connection it may be mentioned that the opening 25 may be made of such a size 50 as to somewhat closely fit the sleeve 19, and yet avoid any chance for corrosion or gumming up of the parts.

To reseat the valve the water supply is 55 shut off and water drawn off the system through main drain valve opening 14. The plug 38 is next removed to allow water in the locking chamber to be drawn off, then the covers 5 and 21 are removed, exposing the locking lever and counterweight. The operator then by pushing back the valve 7 60 against rear wall of casing, releases the locking member 32, which may then be picked up and carried back to its normal position along with valve plate 7. After the valve 65 has been reseated the hand hole plate 21

is put back in place, and a water seal put upon valve 7 through the hand hole 5. After this operation the hand hole 5 is bolted on and air under pressure supplied in any suitable manner. It will be noted 70 that with this construction of locking mechanism there is substantially only one locking member or part which is carried by the sleeve of the valve lever, and no springs or the like controlling the locking which 75 are apt to be rendered ineffective by corrosion. The face 35 and face 36 of the casing being of non-corrodible material, there is no tendency at any time for the parts to stick and become inoperative. While 80 the locking mechanism in the valve shown is arranged to lock the valve open, it might, of course, in some constructions be employed to lock the valve closed this being merely 85 a reversal of the constructions shown, and would depend upon the use to which the valve would be put.

Having thus described my invention, it is obvious that various immaterial modifications may be made in the same without departing from the spirit of my invention; 90 hence I do not wish to be understood as limiting myself to the exact form, construction, arrangement or combination of parts herein shown and described and uses mentioned.

What I claim as new and desire to secure by Letters Patent is:—

1. In a dry pipe valve of the kind described, the combination of a casing provided with 100 an inlet and outlet, a valve controlling the passage of fluid through the casing, and mechanism for automatically locking the valve against a closing movement at any point throughout its opening movement, 105 said mechanism including a stationary part, a movable locking member, and a connection between the valve and locking member whereby movement of the valve toward closed position acts to press the locking 110 member into locking frictional engagement with the stationary part.

2. In a dry pipe valve of the kind described, the combination of a casing provided with an inlet and outlet, a valve controlling the passage of fluid through the casing, and locking means for the valve comprising a stationary part, a movable locking member, and an eccentric connection between the valve and locking member 115 whereby movement of the valve toward closed position acts to press the locking member into engagement with the stationary part.

3. In a dry pipe valve of the kind described, the combination of a casing provided with an inlet and outlet, a valve controlling the passage of fluid through the casing, and locking means for the valve comprising a stationary part, a movable lock- 125

130

- ing member, and a toggle connection between the valve and locking member whereby movement of the valve toward closed position acts to force the locking member into locking engagement with the stationary part.
4. In a dry pipe valve of the kind described, the combination of a casing provided with an inlet and outlet, a valve supported for pivotal movement and controlling the passage of fluid through the casing, and locking means for the valve comprising a stationary part, a strut, and an eccentric connection between the strut and valve whereby movement of the valve toward closed position acts to press the strut into locking engagement with the stationary part.
5. In a dry pipe valve of the kind described, the combination of a casing provided with an inlet and outlet, a valve supported for pivotal movement and controlling the passage of fluid through the casing, and locking means for the valve comprising a stationary part having a curved face, a strut, and an eccentric connection between the valve and strut at one end thereof whereby movement of the valve toward closed position acts to force the other end of the strut into locking engagement with the stationary part.
6. In a dry pipe valve of the kind described and in combination, a casing, a valve arranged therein for controlling the passage of fluid through the casing, and controlling means for said valve, comprising an arm operatively connected with said valve, means for pivotally supporting said arm, means for counterbalancing said arm and valve, and means operative at any point in the travel of the valve for preventing the closing thereof after the same is opened, said means comprising a locking member operatively connected with said arm, and arranged to suitably engage a portion of the casing.
7. In a device of the kind described and in combination, a casing provided with an inlet and outlet, a valve arranged within said casing for controlling the passage of fluid therethrough, controlling means for said valve, comprising an arm operatively connected with the valve at one end and pivotally supported by the casing at the other end, a sleeve connected with said arm, a locking member carried by said sleeve, said locking member arranged to operatively engage the casing wall upon movement of the valve in a predetermined direction.
8. In a device of the kind described and in combination, a casing provided with a plurality of chambers, one chamber having a suitable inlet and outlet, a valve arranged therein and arranged to control the passage of fluid through the casing, means for securing said valve to the casing, comprising an arm adjustably secured thereto and pivotally supported within the casing, said arm provided with a part connected thereto extending into an adjacent chamber, a clutch mechanism arranged in said chamber for locking said valve and arm against movement in one direction, comprising a locking member, means carried by said arm part for supporting said locking member, said locking member arranged to frictionally engage the chamber wall upon movement of the valve and arm in one direction.
9. The combination in a device of the kind described of a casing, comprising a body part with a detachable closure for one end suitably secured thereto, and provided with an inlet therethrough, said part provided with a plurality of valve seats, a valve member suitably formed to coöperate with said seats, an arm pivotally supported within the casing at one end, and secured at its opposite end to the valve member, an arm arranged at said pivoted end at one side thereof provided with a suitably formed lip at the end thereof, a locking member having one end loosely carried by said lip, and the opposite end formed to operatively engage with a portion of the casing wall upon movement of the valve and arm in one direction.
10. In a device of the kind described and in combination, a casing provided with a plurality of chambers therein, and with a separable closure for each chamber, one chamber provided with an inlet through the closure therefor, and with an outlet through the casing, said closure provided with a plurality of valve seats on the inner side thereof, a valve arranged to coöperate with said valve seats, a shaft arranged within the casing, an arm pivotally mounted on said shaft, said arm having its free end suitably secured to the valve and provided with a sleeve at the shaft end extending into an adjacent chamber, a portion of the wall of the casing within said chamber formed with a cylindrical face, with its center of curvature at the pivotal axis of said sleeve, said sleeve extended at one side and formed with a lip thereat, a locking member carried by said lip and provided with a face at one end arranged to operatively engage said cylindrical face, and lock said sleeve against movement, in a direction to close the valve.
11. A device of the kind described, comprising a suitable casing provided with an offset portion at one side having a partition dividing the same into two chambers, a valve member arranged in the casing, an arm secured to and extending from said valve member to one of said chambers, a part secured to said arm and projecting through said partition into said other chamber, a locking member arranged to coöperate

with said part and to engage a portion of the wall of the chamber on movement of said valve in a predetermined direction.

12. The combination in a device of the kind described of a casing formed with a valve chamber, and with a chamber adjacent thereto, a valve member arranged in said valve chamber, and said valve member provided with a rotatable part suitably connected thereto and extended into said chamber adjacent the valve chamber, a locking member arranged in said chamber, said

locking member consisting of a strut arranged at one end for coöperation with said part, and means for engaging the other end of said strut at any position of the valve. 15

In testimony whereof, I have hereunto signed my name in the presence of two subscribing witnesses.
